UNITED STATES PATENT OFFICE.

ALFRED DAHLMAN, OF RIPPLE, OREGON.

UNDERCUTTING-SAW SUPPORT.

Application filed June 30, 1926. Serial No. 119,614.

This invention relates to apparatus for supporting cross-cut saws in undercut sawing operations.

The object of the invention is the provision of an undercutting support for saws, of simple and economical construction, having a clamping device for the swingable supporting arm thereof which is easily and quickly operated to change said arm to any angle of adjustment, and which is positive and secure in its clamping action.

Other objects and advantages of my invention, and objects relating to details of construction, will be readily apparent in the course of the detailed description to follow.

The accompanying drawings illustrate by way of example a preferred form of my invention, in which:

Figure 1 is a view in side elevation of an embodiment of my invention.

Fig. 2 is a plan view of the same.

Fig. 3 is a fragmentary view in vertical section on line 3—3 of Fig. 2.

Referring to said views, the reference numeral 1 indicates a steel bar, desirably of squared cross-section, having a driving point 2 at one end and a driving head 3 at the other. A slide block 5 is provided for said bar formed with a middle portion 6 and two parallel ears 7 spaced apart, between which the bar 1 may be received. Said ears are formed with aligned apertures centrally adjacent their outer ends.

An arm 8 formed of a circular metal rod extends in parallel with the bar 1 and is formed with a right-angled extremity 10 which extends through the ear apertures and is secured therein by cotter-pins 11 extending through holes in said extremity 10 exterior of the ears, respectively. At the opposite end of said arm it is similarly formed with a right-angular extremity 12 upon which a cylindrical saw support 13 is rotatively mounted and may be secured thereon by cotter-pins 15.

The support 13 is formed about its periphery with a plurality of circular grooves 16 extending in parallel planes with the bar 1.

A clamping lever 17 is formed integrally with a cam head 18 of symmetrically curved configuration relative to the longitudinal axis of said lever and is provided with an aperture 20 of approximately the same diameter as the apertures in the ears 7. The aperture 20 is located in the extended lon-

gitudinal axis of the lever and eccentrically with regard to the outer curved or circular end of the head 18, whereby the distances between the center of the aperture 20 and the periphery of said head in transverse lines is less than the distance between said center and the periphery of the head at its extremity in the longitudinal axis of the clamping lever. The opposite end of the clamping lever 17, which overlies the bar 1, is formed with a boss 21 having a screw-threaded bore therein through which extends a clamping screw 22 provided with a crank end 23 by which it may be manipulated.

The head 18 extends between the ears 7 and bears upon the bar 1 with its lateral side face. The extremity 10 of the rod 8 passes through the aperture 20 as well as the apertures in the ears upon each side.

With the apparatus assembled in operative position as described, the point 2 of the bar may be driven into the log which is to be undercut, either horizontally or in any other preferred direction, to securely fix it to bear the weight of the saw and the force of driving the saw in the work to be performed. The arm 8 is then swung about its axis in the arm 7 to bring the supporting roller 13 into proper distance and suitable relation with respect to the log.

When the clamp 22 is loosened this arm 8 may be freely swung to any position, and, when set, may be readily and quickly tightened and clamped firmly by the manipulation of the screw 22 extending through the clamp lever 17 and bearing upon the bar 1, whereby the lever is forced upwardly at its outer end, which tends to swing the aperture 20 out of register with the ear apertures, due to the eccentricity of the aperture 20 relative to the peripheral bearing of the clamp lever on the bar.

The movement required on the clamp head is extremely slight to cause a positive and secure binding effect upon the supporting arm 8 and a relatively slight turning movement of the clamp screw 22 will exert sufficient pressure on the extremity 10 to hold the arm in any position required. The arm may be as readily loosened as it may be set, and thus frequent adjustments of the supporting roller may be made without undue inconvenience. It will be readily seen that the block 5 may be slidably removed along a bar and will be secured in any desired

position thereon, also that the clamp lever 17 may be positioned upon either side of said block by simply removing the outer cotter-pin 11 and withdrawing the angular extremity 10 and reversing the clamp lever before replacing the angular extremity therethrough as before.

5 The device is very simple in its construction and is positive and reliable in its operation. It is strong and serviceable in its design and is thoroughly adapted for the service for which it is intended.

10 From the foregoing description taken in connection with the accompanying drawings 15 the advantages of the construction and application of my improved undercutting saw supports will be readily apparent, but, while I have described the principle of operation of the invention together with the devices 20 which I now consider the best embodiment thereof, it will be understood that the structures shown are merely illustrative, and that such changes may be made therein as will lie within the scope of the following 25 claims.

Having described my invention, what I claim, is:

1. An undercutting saw support, consist-

ing in a bar adapted to be driven into a log, 30 a block slideable upon said bar, a cam-clamp mounted in said block provided with a lever extending longitudinally of said bar having a screw at its outer end bearing upon said bar, and a swingable arm having a rotatable saw-supporting element at one end and pivotally mounted at its other end in said block, 35 said arm-end extending through an eccentric aperture in said cam-clamp whereby the arm is retained in adjusted radial positions.

2. An undercutting saw-support, consisting in a bar, a block mounted upon said bar having a pair of apertured ears upon opposite sides of the bar, a swingable arm provided with means to support a saw at one end and extending at its opposite end through said ears, a cam-clamp mounted between said ears and formed with an aperture through which said arm extends in register with said ear-apertures, said clamp having a bearing upon one side of its aperture upon the bar, and being provided upon its opposite side with a lever, and a screw 45 extending through said clamp-lever and bearing upon the bar.

ALFRED DAHLMAN.
